UNITED STATES PATENT OFFICE.

CARL J. BAER, OF ST. LOUIS, MISSOURI, AND CARL F. JEFFRIES, OF DETROIT,
MICHIGAN.

BOAT.

Application filed July 9, 1927. Serial No. 204,542.

This invention relates to boat propulsion, and more particularly to the propulsion of high-powered boats used for towing purposes.

More specifically the invention embodies the utilization of novel endless chain propelling mechanisms, provided with perforated paddle elements possessing all of the advantages set forth in patent to Baer No. 1,452,059, issued April 17, 1923. Said patent structure however, carried a single row of propelling elements on each side of the boat, whereas the present structure utilizes three or more rows of chain propellers on each side, in combination with means for preventing fouling of the driving mechanisms, and for preventing and undesirable and damaging looseness of the endless chains.

The object of the present invention is the provision of a power boat equipped with driving mechanisms of maximum power and a minimum draft, adapted to haul exceedingly heavy loads in very shallow water.

Another object of the invention is the provision of a boat equipped on each side with a plurality of endless chain propellers, and with means constantly and flexibly supporting each of said chains.

A further object of the invention is the provision of means for separately controlling the operation of each of the propelling chains, including instrumentalities for operating any chain in a forward or reverse direction, and means for adjusting the tension of said chain.

A further object of the invention is the provision of a guard or grating protecting the propelling mechanisms against becoming fouled or clogged by floating articles.

A still further object of the invention is the provision of an endless chain propelling mechanism equipped with paddle elements of such construction that a broken paddle may be replaced with a minimum of time and labor.

The means for accomplishing the above and further objects of the invention, will be made apparent in the following specification, when read in connection with the drawings forming a part thereof.

In said drawings:

Fig. 1 is a perspective view of a tow-boat equipped with our invention.

Fig. 2 is a fragmentary perspective view of a battery of propelling chains for one side of the boat.

Fig. 3 is a side elevation of one of the propelling chains and its supporting mechanisms.

Fig. 4 is a top plan view of a battery of three propelling chains.

Fig. 5 is a perspective view of the means for regulating the tension on the several separate chains.

Fig. 6 is a fragmentary plan view, partly in section, of a portion of one of the propelling chains.

Fig. 7 is a sectional view on the line 7—7 of Fig. 3.

Fig. 8 is a section taken on the line 8—8 of Fig. 6.

Fig. 9 is a section taken on the line 9—9 of Fig. 6.

Fig. 10 is a front plan view of a paddle element showing the chain and an idler wheel partly in section, and,

Fig. 11 is a perspective view of a bracket for supporting the paddle element.

Now referring specifically to the drawings, in which similar reference characters indicate like parts throughout the several views, A is a boat body, provided with a cabin B, in which the motors and controls are housed.

Extending transversely through the body of the boat A, below the deck, are sills 1, of angle iron, forming the main supports of a frame-work which carries the propelling chains to be hereinafter described.

Secured to the outer ends of the centrally located sills 1, are metallic arches 2, which may extend through the top of the cabin B, and a rail 3 extends in longitudinal parallelism with the boat, and connects the outer ends of the fore and aft sills 1, 1, on each side, as clearly shown in Fig. 1.

Rigidly secured to the sills 1^a and 1^b on each side of the cabin B, are posts 4—4, which are secured to the top, horizontally-extending rails 5, 5 of truss members made up of said top rails 5, curved lower rails 6, an intermediate rail 7 and connecting posts 8, as best seen in Fig. 3. It is to be understood that parallel truss members composed of the rails 5, 6 and 7 connected by the posts 8, and depending from the sills 1^a and 1^b, form supporting frames for the endless propelling chains.

pelling chains, and that as many of such chains as desired may be carried on each side of the boat.

As shown in Fig. 3, a driving sprocket 9 mounted on a shaft 10, is carried by the front end of the supporting frame, and an endless chain 11 is trained over said wheel and also over a rear sprocket wheel 12 mounted on a shaft 13. The chain 11 may be of ordinary construction but of great strength and is provided with pivoted links having pivot pins surrounded by anti-friction rollers. Each chain 11 carries a plurality of spaced paddle elements 14, bolted to the links as will be hereinafter explained, each paddle 14 being provided with a plurality of perforations whereby to permit the passage of a portion of the water therethrough, a great advantage fully explained in our patent heretofore referred to.

The boat A is here illustrated as equipped on each side with a battery of three propelling chains and provided with partitions 15 which separate one chain from the chain 11 adjacent. As shown most clearly in Figs. 3 and 4, a drive chain 16 is trained over the sprocket 9, carried by the axle 10 of each of the chains 11, whereby to rotate the shaft 10 in either direction. It is deemed unnecessary to here illustrate the means for rotating said shafts. Obviously a separate reversible motor may be provided for the purpose of rotating each shaft, well known clutch mechanisms being interposed to permit rotation of said shafts in either direction. It is to be understood that such powered mechanism would be provided as to be capable of selectively rotating any shaft 10 in either direction, irrespective of the direction of rotation of any one of the other shafts.

In order to take up any undesirable slack in the chain 11, each end of the shaft 13 of the sprocket wheel 12, is mounted in a squared bearing 17, slideable forwardly and rearwardly in flat tracks formed between plates 18, 18, supported by the rear ends of parallel rails 7, 7. A worm shaft 19, supported by a bracket 20, carried by the rail 7, is in screw-threaded engagement with an aperture in the inner end of the bearing 17. The inner end of the shaft 19 carries a beveled gear 21, in mesh with a co-operating beveled gear 22, mounted on the end of a transversely extending shaft 23, having its inner end journaled in a bracket 24, mounted on the rail 7. The outer end of the shaft 23 will be provided with a crank handle, for manual operation, or with means for connection to and operation by one of the motors, and will be equipped with suitable ratchet mechanism whereby to releasably retain it in position.

As clearly illustrated in Figs. 2 and 3, we provide means, such as a metallic cable

25, for supporting the chain 11 between the necessary idler rollers 26, and to thereby eliminate the destructive vertical vibrations of the chain during its travel at high speed. As will be hereinafter more specifically explained, the cable 25 tracks in grooves formed in the idlers 26, on the top flight, and in sheaves 27, on the bottom flight. A plurality of the idler rollers 26 are mounted along the upper flight of the chain, each 70 roller being mounted on a shaft 28, having bearing in a bracket 29, mounted on the rail 5. The sheaves 27 are carried by shafts 30, having a vertically movable bearing formed by blocks 31 mounted in a vertical 75 track provided in the posts 8. In order to raise or lower the blocks 31, to tighten or loosen the chain 11, we provide on each block 31 on each side of the sheave 27, a screw threaded shaft 32, carrying a beveled gear 80 33 at its upper end, said shaft extending through and in screw-threaded engagement with its associated block. Extending transversely of the shafts 32, are telescopically positioned operating shafts 34, 35 and 36, 90 it being noted that each of said shafts 34, 35 and 36, is provided with beveled gears 37 meshing with the gear 33 carried on the vertical shafts 32, whereby a rotation of any of the shafts 34, 35 and 36, will cause a vertical movement of the associated sheave 27, to tighten or loosen the chain 11. The shafts 34, 35 and 36 extend outwardly beyond the frame-work towards the boat A, and the ends thereof project, one beyond the other, for the attachment of hand levers 38, or the end of each shaft may be equipped with a sprocket wheel and connected chain, whereby to rotate the shafts by power from the motor, as will be understood. Suitable 100 ratchet mechanism will be provided to retain the shafts in any adjusted position.

Fig. 3 shows means for separately and automatically preventing slack in the cable 25. Centrally of the frame, an idler 39 is mounted on a stub shaft 40, having bearing in a block vertically slideable in a track formed in the central post 8. A coiled spring 40 rests upon the top of the bearing block, and above the spring is provided a pressure plate 110 41, secured to the headed bolt 42, screw-threaded into the top of the rail 5. The cable 25 is passed around the lower portion of the idler 39, and during the travel of the chain 11 and cable 25, the idler 39 rides upwardly and downwardly in its bearings, under control of the spring 41. Any adjustments to vary the tension of the spring may be made by rotation of the bolt 42.

Each paddle element 14 is preferably, though not necessarily, formed of an elongated plate of metal, provided with a plurality of perforations extending transversely therethrough, as best illustrated in Fig. 130

10. In the preferred embodiment here illustrated the upper edge of the plate 14 is cut away to provide for entry of the chain 11, and the periphery of the idlers 26 and the 5 sheaves 27. In Fig. 11 is shown a bracket 43 for securing the paddle 14 to the chain 11. The bracket is preferably formed of oxidized steel, and is substantially star-shaped, having laterally and downwardly extending bifurcated arms 44, 45 and 46, adapted to be bolted or riveted to the paddles 14, and very strong diverging upright arms 46, 46, perforated to permit the insertion of bolts 47, which secure the arms 46 to the edges of the 10 cut away portion of the paddle 14. Formed on the lower portion of each of the arms 46, 46, are laterally-extending integral braces 48, 48, perforated to receive bolts 49, 49, whereby to secure the paddle to suitable portions 15 of the links of the chain 11. This entire structure is clearly shown in Figs. 10 and 11.

Each battery of chains is protected by a guard structure composed, in part, of spaced 20 rods, the structure completely enveloping the chains at each end, as well as laterally and below. As illustrated in Fig. 1, metallic bars 50, 50 depend from the front and rear rails 1, 1, the lower ends of the bars being 25 connected by a brace rod 51, as many of such rods as required for strength being secured to the rails 1. A plurality of properly placed guard rods 52, extend between and are secured at each end to the brace rods 51, throughout and beyond the length of the 30 chain. The ends of the rails 3 extend outwardly beyond and above the end brace rods 51, guard rods 53, having eyelets surrounding the brace rods 51, and having 35 their outer ends connected by a flat plate 54, form a pivotally mounted gate. A cable 55 40 is secured to the plate 54 and extends over a pulley mounted on the end rails 1, 1, into the cabin B, and by means of the cable the gate may be raised when desired, or released 45 for gravitation. Apertured plates 56, 57 and 58 are vertically carried between the rail 3 and the brace rods 51, and such plates 50 may either be permanently fastened in position, or pivotally mounted for swinging 55 action, as desired.

The space directly above the chains 11, and opposite the cabin B, is covered by a roof composed of a plurality of boards 59, each 55 of which is removable to give access to the chains for purposes of repairs, replacements, etc.

Rudders 60 are placed fore and aft on each side of the boat, and in front and at 60 the rear of each chain battery. Each rudder is provided with a shaft 61 journaled in a rail 1 as shown, and cables 62 are connected to an arm 63 on the shaft 61, the cables extending into the cabin B, convenient 65 to the operator.

From the foregoing it will be clear that we have provided a boat structure equipped with a battery of endless chain propelling mechanisms on each side, each chain of each battery being susceptible of operation in any 70 direction, separately tensed, or so vertically flexed that it may be elevated out of the water, and being provided also with additional means for longitudinally adjusting the slack. In addition thereto we have provided a cable for supporting each chain, in combination with instrumentalities automatically maintaining the proper tension on each cable. Part of the work of a boat as herein described will be performed in the 75 waters of shallow tributaries of the main inland waterways, the boat being employed as a tow for a plurality of barges. Such small creeks or rivers are incapable of commercial navigation, except with boats of shallow 80 draft, and great power, and unless the boats are provided with means for overcoming the various conditions incident to navigation, in such waters.

A boat for the service as above described, should be capable of movement in either direction, therefore the boat as just described must be equipped with means for reversing the direction of travel of its chains. It must be able to turn within very restricted limits, 90 and we have therefore provided our boat with means whereby any one or more chains of battery on one side thereof may be running in one direction, while any one or more chains of the battery on the opposite side 95 may be running in a reverse direction. Such operation would obviously tend to abruptly swing the boat around, both rudders being properly positioned. In certain instances one or more of the paddles 14 may be accidentally broken off, resulting in a decreased 100 efficiency of a battery on one side of the boat. To cover such contingencies, we have provided the shafts 34, 35 and 36, with the associated gears 37 in mesh with the gears 33 105 carried on the shafts 32, as explained. The bearing slots in the posts 8 are of such vertical length that the blocks 31 may rise in said slots to such a height as to lift the sheaves 27 110 above and off the lower flight of the chain. Under such circumstances the shaft 23 is rotated to push the sprocket wheel 12 rearwardly. Such movement manifestly causes a partial reverse rotation of the wheel 12, 115 since the upper flight of the chain is rigidly held against longitudinal movement by the wheel 9 and the idlers 26, and the parts are so proportioned that the wheel 12 may be moved rearwardly to an extent sufficient to lift the paddles of the lower flight entirely 120 out of the water. The motor driving this chain is of course out of operation at this time, and any broken paddle is easy of access for repair, by lifting the plates 54.

It is important to protect the chains 11 130

against the drift-wood which floats on the water, and we have therefore provided the guard structure as clearly shown in Fig. 1. Each of the gates 54 may be raised and lowered, as explained, the front gate of course being always closed when the boat is traveling through the water, and the rear gate opened in order to permit the egress of any drift which may have passed through the 10 openings at the front and sides. It will also be noted that the rods 52 lie in a plane substantially below the lowest reach of the paddles 14. In the navigation of shallow rivers containing many alluvial deposits of sand 15 or silt, when the rods 52 contact such deposits they cut long furrows therein, thereby loosening the deposits and permitting them to be washed out by the swift flow of water under the chains.

20 The rudders 60 are placed within the guard housings, one near each end of each chain battery. Such location not only protects the rudders from injury, but locates them as nearly as feasible towards the ends of the 25 boat, where they will be most effective.

In actual practice the rods 52 and 53 may be made detachable if desired, by providing them with screw threads at the ends, adapting them to be connected to threads in apertures provided in the brace rods 51, and in the plates 54, a turnbuckle being provided in the length of each rod 51. Under these circumstances a broken rod could be quickly replaced.

35 As explained at length in the Baer patent No. 1,452,059 heretofore referred to, great advantages are derivable from the use of perforated paddles for boat propulsion. By the prevention of cavitation, because a certain amount of water passes through one paddle to feed the next paddle, a chain composed of a plurality of perforated paddles may run at maximum efficiency in a smaller volume of water than would be required for 45 maximum efficiency of a chain composed of solid paddles. In so far as we are aware, we are the first in the art to provide a drive mechanism equipped with perforated paddles, in combination with a grating or guard 50 completely surrounding the mechanism. For many years the extreme desirability of a protecting guard around and beneath boat driving means, has been generally recognized. Such guards have hitherto been considered commercially impracticable however, because the guard always prevented access of a certain amount of water to the propelling mechanisms, resulting in an unsatisfactory power ratio in proportion to the ex- 55 panded energy. A drive chain such as herein described, can operate at maximum efficiency in from 10 to 15% less water than can a chain or a wheel equipped with solid paddles. Consequently, assuming that the 60 guard surrounding the chain robs the latter

of from 10 to 15% of water, we have provided a drive mechanism capable of developing maximum power, and guarded at all points against injury to the paddles by drift wood floating on the water, or by obstructions on the bed of the river.

70 Modifications of the herein disclosed structure may be suggested to those skilled in the art, but our invention covers all embodiments falling fairly within the scope of the 75 appended claims.

We claim:

1. A boat provided on each side with a battery comprising a plurality of propelling chains, means for selectively driving any 80 chain on either side in any direction longitudinally of the boat, a rudder positioned at each end of each battery, and a perforate guard member on each side completely enclosing the immersed portion of the chains 85 of each battery and the associated rudders.

2. A boat provided on each side with a propeller chain, an endless cable supporting each chain along its upper flight, and means for regulating the tension of said chain. 90

3. A boat provided on each side with a propeller chain, an endless cable supporting each chain along its upper flight, and means automatically maintaining the tension on 95 said cable.

4. A boat provided on each side with a propeller chain, an endless cable supporting each chain along its upper flight, means for regulating the tension on each chain, and means automatically maintaining the tension on each cable. 100

5. A boat provided on each side with a battery comprising a plurality of propeller chains, an endless cable supporting each chain along its upper flight, means for selectively adjusting the tension of any chain in 105 a battery, and means automatically maintaining the tension of each cable.

6. A boat provided on each side with a battery comprising a plurality of propeller chains, an endless cable supporting each chain along its upper flight, means for selectively adjusting the tension of any chain in a battery, means automatically maintaining the tension of each cable, and a rudder operatively mounted at each end of each battery. 110

7. A boat provided on each side with a battery comprising a plurality of propeller chains, an endless cable supporting each chain along its upper flight, means for selectively adjusting the tension of any chain in a battery, means automatically maintaining the tension of each cable, a rudder operatively mounted at each end of each battery, and a perforate guard completely enclosing the immersed portion of the chains of each battery and is associated rudders. 125

8. A boat provided on each side with a battery comprising a plurality of propeller chains, an endless cable supporting each 130

chain along its upper flight, means for selectively adjusting the tension of any chain in a battery, means automatically maintaining the tension of each cable, a rudder operatively mounted at each end of each battery, and a foraminous guard completely enclosing each battery and its associated rudders, said guard being provided at each end with a pivotally mounted gate.

10 9. A boat provided with an endless propeller chain, a plurality of idler rollers adapted to support said chain along its upper flight, an endless cable mounted for travel in parallelism with said chain and over said rollers, said cable operating to support the upper flight of the chain between the rollers, and means for automatically maintaining the tension on said cable.

10 10. A boat provided with a propeller chain carried by a frame, a plurality of idler rollers mounted on said frame and adapted to support the upper flight of said chain, a tension roller mounted in a sliding bearing located below the plane of said chain, a cable trained over said idler rollers and under said tension roller, and means resisting upward movement of said tension roller.

11. A boat provided with a propeller

chain carried by a frame, a plurality of idler rollers mounted on said frame and adapted to support the upper flight of said chain, a tension roller mounted in a sliding bearing located below the plane of said chain, a cable trained over said idler rollers and under said tension roller, means resisting upward movement of said tension roller, said means comprising a coiled spring exerting a downward pressure upon the bearing of said roller.

12. A boat provided with a propeller chain carried by a frame, a plurality of idler rollers mounted on said frame and adapted to support the upper flight of said chain, a tension roller mounted in a sliding bearing located below the plane of said chain, a cable trained over said idler rollers and under said tension roller, means resisting upward movement of said tension roller, said means comprising a coiled spring exerting a downward pressure upon the bearing of said roller, and means for regulating the pressure of said spring.

In testimony whereof we affix our signatures.

CARL J. BAER.

CARL F. JEFFRIES.
